FLOW-DIRECTING CONE FOR SCREW PROPELLERS

Application filed June 12, 1929, Serial No. 370,283, and in Italy June 30, 1928.

The present invention relates to a fixed device applicable in front of a propeller and coaxial with same serving to impart a divergent direction to the fluid currents which tend to converge towards the boss of the propeller so as to meet the blades of the propellers in areas at some distance from the axis which are accordingly more efficient.

It is known that parts of the propeller blades close to their foot on the boss have an efficiency which is almost null because owing to their comparatively low peripheral speed and in order to give a useful impulse their pitch should be much greater with grave losses due to useless lateral impulses imparted to the fluid. For this reason there is a tendency to suppress the parts of the blades too close to the axis by making the boss very large and giving considerable width to the blades in order to compensate for the loss of propelling area in the central portion.

This arrangement, however, if in various instances it has yielded useful results, especially in order to avoid cavitations in propellers running at a high number of revolutions, has not at all removed the drawbacks above complained of, and in addition is not readily applicable to propellers of a large diameter and slow rotation in which the enlarged bosses would have to assume inconvenient proportions and too heavy weights.

The device forming the subject matter of the present invention not only provides in the propeller a fictitious enlarged boss with the advantages mentioned above, but makes the fluid reach the areas of greater efficiency of the blades in larger quantity and with a velocity and direction better calculated to increase the propulsion efficiency.

The same device has in addition the secondary but highly important purpose on high speed vessels, of eliminating the eddies which are formed in the fluid by the inevitable breach of continuity existing between the stern expansion around the axis and the boss of the propeller.

In order to make the nature of the invention better understood a preferred form of execution of same applied by way of example to a vessel with one single central propeller

is described below with reference to the attached drawings, in which:

Fig. 1 represents the longitudinal view of the stern portion of the vessel with the propeller and the device according to the invention 65 partially shown in section;

Fig. 2 represents the same arrangement viewed from above in horizontal section drawn according to the water line II-II.

As it is known the stern post 1 of a screw 60 steamer 2 has in correspondence with the shaft a coaxial eye in which is fixed the tube of the propeller shaft and which is thereupon surrounded by the hull 3 suitably enlarged. Between the boss of the propeller 2 and the rear packing 5 of the said eye on the stern post there is always a superficial breach in continuity creating eddies in the fluid currents, which following the line of the hull, tend to meet together by converging towards 70 the shaft. In order to avoid this convergence and these eddies according to the invention there is applied to the eye or boss of the propeller post a sleeve of a cylindrical conical shape 6 which is fixed on the expanded outer skin by means of a suitable forward collar 7 duly formed in order to constitute a perfectly smooth surface with the outer skin itself. The said sleeve 6 is of a metal material of wrought or cast plate as the case may 80 be, and its attachment to the expanded outer skin can be effected by brazing, by autogenous welding or by countersunk bolts 8 or in some other suitable manner for constituting a strong connection without creating additional resistance owing to parts projecting 85 beyond the smooth surface. The rear portion of the sleeve 6 is widened in a cone or rumpet as close to the propeller blades as

practicable so as to avoid shocks and obstructions. The inclination of the said conical part shall be such as to diverge the fluid currents towards the most suitable areas of the blades and it will therefore be designed in each case in function of the speed of propulsion of the vessel, the speed of rotation of the propeller and the relative dimensions of the latter as well as of its particular characteristic data. The said inclination may therefore vary from zero, corresponding to a cylindrical 100

sleeve, to a very high value not usually exceeding 45°. It will be readily understood that the liquid currents running alongside of the vessel and tending to meet at the stern, will by the said diverting cone 6, be deviated and made to diverge according to the arrows shown in the drawings, the results designed by the invention being thus attained. Simultaneously, between the sleeve and around the boss there will be formed a mass of water, which will be drawn along by the vessel in her motion, remaining stagnant in relation to the propeller; this comparatively motionless mass of water will not absorb any power and will consequently constitute an artificial boss about the real boss, with an increase in efficiency and the elimination of cavity formation if any, without any addition of useless weight and space.

Although for reasons specified the device has been described as applied to a vessel with one single central propeller, it must, of course, be understood that the said device with the necessary variations in adaptation can be applied to vessels with multiple propellers, in which case one diverting cone should be arranged for each propeller and at the ends there would be attached appendices forming a head to the lateral bosses of the sternpost or at the most convenient points. The invention is not contemplated as being limited to the example referred to, but also embraces all possible applications on the bases of the fundamental principles of the said invention.

Having now described and ascertained the nature of our invention and in what manner the same is to be performed we declare that what we claim is:

A fluid directing device for use with screw propellers of ships comprising a sleeve adapted to surround the shaft on which the propeller is mounted, and having a free end arranged closely adjacent said propeller, and means for directing a flow of fluid acentrically of said propeller, said means comprising an outwardly flared peripheral flange on the propeller end of said sleeve, and enclosing a portion of the hub of the propeller.

In testimony whereof we affix our signatures.

RAOUL TUROLA.
CARLO GIUSEPPE FASCETO.
